UNITED STATES PATENT OFFICE.

ROBERT E. THOMPSON, OF DES MOINES, IOWA.

GOLF BAG.

Application filed May 13, 1925. Serial No. 29,950.

The object of my invention is to provide a golf bag of very simple, durable and inexpensive construction, constructed in a form tapered from its bottom to its top and tapered to a sufficient degree that the bag will readily stand upright.

A further object is to provide in such a bag at the upper end thereof a flexible member provided with a series of loops for affording means for holding the clubs separated in definite relative positions.

Still a further object is to provide in such a bag a reinforcing member extending along the upright wall thereof and in-turned at its lower end and secured to the bottom of the bag for affording better reinforcement.

With these and other objects in view, my invention consists in the construction, arrangement and combination of the various parts of my golf bag, whereby the objects contemplated are attained, as hereinafter more fully set forth, pointed out in my claim, and illustrated in the accompanying drawings, in which:

25 Figure 1 is an elevation of a golf bag embodying my invention.

Figure 2 is a detailed, sectional view taken on the line 2—2 of Figure 1.

Figure 3 is a top or plan view of the bag;

30 and Figure 4 is an inverted, plan view of one of the forms in which the bag may be embodied.

In the accompanying drawings, I have used the reference numeral 10 to indicate generally the bottom of my improved golf bag, which may be round, as in the form illustrated in Figures 1 and 2, or triangular as illustrated at 10^a in Figure 4 or rectangular or oval or any desired shape.

The bottom 10 may be of fiber or any suitable material and preferably has its edges at its periphery turned down as at 11.

The golf bag has a side wall 12 preferably made of leather, canvas or other suitable flexible material reinforced with upright wires, bars or the like 13 of sufficient rigidity to prevent the bag from collapsing from top to bottom.

50 One of the important features of my bag is its tapered shape. The bag is of considerably greater diameter at the bottom than at the top as clearly illustrated in Figure 1. Such a bag should have enough flare from top to bottom or taper from bottom to top,

so that the vertical line through the center of gravity will always extend through the bottom. That is to say, the outline of the bottom should be large enough so that the bag may stand upright by itself, and the overhanging heads of the clubs at the upper end of the bag will not cause it to tip over.

In order to further contribute to the desired result, towit, a golf bag structure in which the parts are so arranged that the bag will stand upright when placed on the ground or the floor, I have provided another feature. At the top of the bag is a reinforcing peripheral member 14. Inside the bag near the top there is provided a series of dividers for holding single clubs. These series of dividers may be formed by taking a flexible member 15, fastening it at regular intervals 16 to the side wall of the bag and thus forming a series of loops 17. These loops 75 cooperate with the tapered shape of the bag for producing a bag which will properly stand upright in the following manner:

It will be readily understood that it is harder to make a bag stand upright if all of the clubs tend to lean in one direction. Where the clubs are slipped through the loops 17, they are divided around the wall of the bag, so that they do not all tend to hang over one side of the bag. These dividers therefore combined with the tapered shape of the bag insure that the bag will stand upright when placed on the ground.

Secured to the upright wall of the bag is a series of reinforcing members 13, which 90 may be of any desired material. At their lower ends the members 13 are in-turned, as at 18, and are secured to the bottom 10 by rivets 19 or other suitable means.

It is, of course, important in order to make 95 a bag which will stand upright that the side walls should be connected with the bottom so that the bag will not collapse at the lower end.

I mention this in particular because most 100 golf bags are made with upright reinforcing members which terminate just short of the bottom so that the leather or canvas of the side wall might readily collapse adjacent to the bottom and such bags could not be made 105 to stand upright.

The bag is provided with a suitable handle 20 on its outside so located that the bag with the clubs therein balances when grasped by the handle.

The flared bottom helps to secure a better balance for the bag than can be secured with bags of the ordinary construction.

A suitable carrying strap 21 may be fastened to the bag.

A closure strap 23 may be provided at the top of the bag, but these latter are features which are not peculiar to this bag. The bag proper may be provided with the usual accessories, such for instance as the ball pocket 24 on the outside of the bag.

The bag may be made of any proper material and may be varied in shape as has been heretofore suggested so long as it retains the real features of my invention, and it is my intention to cover by my claim any such modifications in details of structure or use of mechanical equivalents as may be reasonably included within the spirit of my invention.

I claim as my invention:

A golf bag of the character described comprising a truncated cone shaped bag provided with a bottom member, reinforcing rods secured to the wall of said bag, feet 25 formed on the bottom ends of said rods and riveted to said bottom member, a flexible strip secured to the inside of said wall adjacent the top thereof at spaced intervals for receiving the handles of golf clubs for the 30 purpose of distributing their weight around the top of the bag to enable it to stand in upright position.

Des Moines, Iowa, December 31, 1924.

ROBERT E. THOMPSON.
